Primary Examiner—Wallace R. Burke*Assistant Examiner—Joel Sincavage**Attorney, Agent, or Firm—Zarley, McKee, Thomte, Voorhees & Sease***[57] CLAIM**

The ornamental design for a shoe-attached remote control for operating a trolling motor, as shown and described.

DESCRIPTION

FIG. 1 is a perspective view of a shoe-attached control for operating a trolling motor showing my new design; FIG. 2 is a front elevational view thereof; FIG. 3 is a top plan view thereof; FIG. 4 is a rear elevational view thereof; FIG. 5 is an elevational view taken from the left side of FIG. 2; FIG. 6 is a bottom plan view thereof; FIG. 7 is an elevational view taken from the right side of FIG. 2; and, FIG. 8 is a perspective view thereof shown attached to a shoe. The broken line showing of the shoe is included for the purpose of illustrating environmental structure only and forms no part of the claimed design.

FIG. 1

FIG. 2
